UNITED STATES PATENT OFFICE.

HERBERT C. KELLOGG, OF DETROIT, MICHIGAN.

LIQUID-COOLING APPARATUS.

Application filed September 12, 1927. Serial No. 218,890.

The invention relates to improved apparatus for the cooling of liquids and particularly for the cooling of liquids subject to variable or intermittent draft. The present application constitutes a continuation in part of my application Serial No. 745,162, filed October 22, 1924.

Some of the chief objects of the invention are comprehended in the provision of apparatus for the cooling of liquids subject to variable draft or having a variable heat content, characterized by (a) very high cooling efficiency, (b) large cooling capacity in proportion to the capacity of the refrigerating apparatus employed, (c) close automatic regulation of the temperature of the liquid drawn, up to the maximum capacity of the apparatus, notwithstanding wide variations in the rate of draft or heat content of the liquid, (d) a high degree of compactness for a given cooling capacity, (e) minimized heat absorption from the surrounding atmosphere, and (f) adaptability of a given size of the cooling apparatus proper to a relatively wide range of cooling capacities.

A further object of the invention is the provision of a liquid cooling apparatus of the character above indicated which is especially adapted for the cooling and dispensing of carbonated beverages.

Other objects of the invention more or less ancillary or incidental to the foregoing, as well as the manner in which all of the various objects are attained, will be apparent from the following description which sets forth in connection with the accompanying drawings one form of preferred apparatus suitable for the practice of the invention.

In the drawings:

Fig. 1 is a perspective view of an apparatus embodying my improvements and which is especially adapted for the cooling and dispensing of beverages.

Fig. 2 is a central vertical section through the apparatus shown in Fig. 1 with some of the parts shown in elevation.

Fig. 3 is an enlarged central vertical section of the primary cooling unit of the apparatus.

Fig. 4 is a vertical sectional view of the thermostatic switch with some of the parts shown in elevation.

Fig. 5 is a fragmentary elevation showing a modified form of the thermostatic control devices.

The apparatus comprises a cooling unit

in which liquid refrigerant is vaporized and through which the liquid to be cooled passes in order to give up its excess heat to the refrigerant, and means for withdrawing the vaporized refrigerant from the cooling unit and again liquefying it. Where, as in the case of the apparatus illustrated, a carbonated beverage is to be cooled, I prefer to also provide a chamber in which the excess charging gas can be liberated before the beverage is dispensed. This latter chamber may also perform the function of a secondary cooler, as will later be explained.

Referring in detail to the construction illustrated, 1 designates in its entirety the frame and casing structure. This structure is divided by a horizontal partition 2 into a lower section 3 and an upper section 4. The lower section 3 has a base or floor 5 which is provided with feet or pedestals 6 adapted to rest upon the floor or other suitable support.

Within the upper section 4 of the casing is disposed a tank 7 adapted to hold a body of liquid refrigerant 8, such for example as sulphur dioxide, and permit vaporization thereof when the refrigerant absorbs heat. Refrigerant is withdrawn from the tank 7 in vapor form and returned to it in liquid form by the refrigerant liquefying apparatus 9 which is housed in the lower part 3 of the casing. This refrigerant liquefying apparatus comprises a compressor 10 driven by an electric motor 11 which drives the compressor through suitable gearing enclosed in casing 11^a, and a condenser 12 in which the compressed gaseous refrigerant delivered from the compressor 10 is cooled and liquefied. Water for cooling the compressed gas in the condenser 12 is supplied through the pipe 13 and carried off to waste through the pipe 14, these pipes being connected to the usual cooling coil (not shown) in the condenser. The suction side of the compressor 10 is connected by the pipe 15 with the vapor space 16 above the liquid refrigerant 8 in the tank 7, the upper end of the pipe 15 being connected with the upwardly inclined open-ended tube 15^a within the tank 7. The condenser 12 delivers the refrigerant liquefied therein into a sump or passage (not shown) formed in the crank case casting of the compressor 10 and connected with this sump is a pipe 17 which at its upper end connects with a valve 18 actuated by float

19 partially submerged in the liquid refrigerant.

erant 8, this float valve serving to admit liquid refrigerant from the condenser and maintain it at a predetermined level in the tank 7.

I do not show and describe the motor driven compressor and condenser in detail, as any suitable form of refrigerant liquefying means adapted to be automatically started and stopped can be employed. It may be 10 noted, however, that the motor driven compressor and condenser apparatus illustrated in the drawing is one commercially well known at the time of the filing of my original application and reference may be made, 15 for further details of its construction and operation to Letters Patent of the Republic of France No. 547,971, dated February 27, 1922.

The operation of the compressor is automatically controlled by a thermostatic switch device 20. A thermostatic bulb 21 which extends into the tank 7 and contacts with the liquid refrigerant therein communicates through a capillary tube 22 with 25 the switch device to actuate the same by the expansion of a suitable liquid contained in the bulb and tube. Various expansible liquids can be employed for this purpose, depending upon the character of the switch. 30 With a suitable switch mercury, for example, can be employed as the expansible liquid. However, with the form of switch illustrated a liquid should be used having a marked vapor pressure throughout the range of temperatures at which the cooling apparatus operates. Some of the liquid refrigerant employed in the apparatus, such as sulphur dioxide, serves this purpose satisfactorily. 40 As shown in Figs. 2 and 4 the thermostatic switch has an enclosing casing 23 for the switch proper on the top of which is secured a cylinder 24 which encloses a vertically compressible and expansible gas tight bellows 25. This bellows at its lower end has a gas-tight connection with the lower end of the cylinder 24. The capillary tube 22 communicates through the top of the cylinder 24 with the interior space between the cylinder and the bellows and the expansible thermostatic fluid fills this latter space as well as the capillary tube and the bulb 21. The top plate or disc 25^a of the bellows is rigidly connected to a depending plunger 26 45 which slidably engages a threaded sleeve 27 adjustably mounted in a bottom plate 24^a of the cylinder. By turning the threaded sleeve in the plate 24^a it can be adjusted up and down and can be secured in adjusted position by lock nut 28. A member 29 resting upon the upper end of the sleeve 27 serves as an abutment for the lower end of a compression spring 30 the upper end of which engages a flanged ring 31 55 slidably mounted on the plunger 26. Ob-

viously adjustment of sleeve 27 varies the tension of the spring 30 thus varying the force with which the spring is adapted to resist compression of the bellows and restore the same to its expanded position. A light coil compression spring 32 at its upper end engages the recessed under side of the sleeve 27 and at its lower end engages adjustable abutment nuts 33 on the plunger 26. Adjustment of the nuts 33 varies the tension of the spring 32 which in turn tends also to vary the tension in the heavier spring 30. It will be seen that the pressure of the refrigerant fluid in the bulb 21, transmitted through the tube 22, tends to depress the bellows and the plunger 26 and that the amount of pressure necessary to depress the plunger will depend upon the tension of the springs 30 and 32.

The electric switch proper 34, mounted on the floor of the casing 23 is of the snap or toggle type. This kind of switch is well known and it will therefore suffice to state that the switch illustrated comprises a pair of fixed terminals or electrodes 35, 36 and a movable member or electrode 37 which is mounted on a resilient lever 38 pivoted on post 39. The switch lever 38 is actuated by a toggle spring 40 connected at one end to the lever and at its other end with a depending link 41 which is connected to one end of an actuating lever 42 pivoted at its other end to a vertically adjustable support 43. A second lever 44 is in turn pivoted at 45 to the lever 42 and also carries an abutment pin 44^a which engages an upward extension 42^a of the lever 42. The lever 44 also carries a flat spring 44^b which is adapted at its free end to be engaged by the lower end of the plunger 26 which passes through an opening provided in the lever 44 for this purpose. A shoulder 26^a on the plunger engages a member 44^c on lever 44 to limit the flexing of the spring 44^b, while a collar 26^b on the lower end of the plunger is adapted to engage the member 44^c to elevate the lever 44 and with it the lever 42. When the bellows and the plunger 26 are depressed the levers 44 and 42 and the link 41 are moved downward and the switch closed, while upward movement of the same parts causes the switch to open. 46 is a pivoted latch device which engages the switch arm 38 to hold it in closed position until the link 41 has been raised nearly to its uppermost position whereupon the lever 47 is actuated by the link 41 to engage the latch 46 and disengage the same from the lever 38. This insures a sudden snap action for the opening of the switch.

It will now be seen that when the temperature of the thermostatic fluid in the bulb 21 rises the resultant increase of its vapor pressure will cause compression of the bellows device 25 with resultant closing

of the switch 34 and starting of the motor driven compressor; whereas the lowering of the temperature of the thermostatic fluid decreases its vapor tension and this permits the bellows 25 to expand under its inherent resiliency and that of the spring 30 with the result that the switch 34 is opened. It is obvious that a substantial movement of the bellows is necessary to actuate the toggle switch both in closing and opening and that this movement corresponds to a certain range of temperature change of the thermostatic fluid. By suitable adjustment of the springs 30 and 32 the mean temperature of this temperature range referred to can be varied up and down and also the extent of the temperature range itself can be varied. This need not be explained in further detail since this form of switch was well known at the time of the filing of my original application, being in fact the same as that illustrated in the French patent above referred to.

In the switch device illustrated there is to the left of cylinder 24 a similar cylinder housing another bellows device adapted to actuate the switch lever under certain emergency conditions, but these emergency devices need not be described as my present invention is not concerned with them.

Within the tank 7 and immersed in the liquid refrigerant therein is a metallic coil 48 which is connected at one end with an inlet pipe 49 for the liquid to be cooled and at its other end with a discharge pipe 50. The coil 48 is made of suitable dimensions as to cross-sectional capacity and length as will later be explained. The discharge pipe 50 may lead directly or indirectly to the means which control the flow of the liquid to be cooled. In the present case the apparatus is designed to cool a charged beverage and the pipe 50 accordingly leads into a gas liberating tank 51 which is disposed above and rests upon the top of the refrigerant tank 7 in heat conducting relation therewith. The discharge end of the pipe 50 is controlled by a valve 52 actuated by a float 53, this float valve serving to maintain a predetermined level of the liquid in the tank 51. This liquid, having been cooled to the desired temperature in the coil 48, is maintained at substantially the same temperature in the tank 51 by reason of the fact that the bottom of the tank 51 contacts with the top of the tank 7 so that the two tanks and their contents are maintained at substantially the same temperature. Draft faucets 54 are connected by tubes 55 with the lower part of the tank 51 and serve to dispense the cooled liquid therefrom. The upper part of the chamber in the tank 51 is connected by a pipe 56 with the water waste pipe 14 through a pressure regulating valve 57 which permits escape of the carbonic gas when the

pressure of the latter arises above a certain point, the pressure being indicated by a gauge at 58. The refrigerant tank 7 and the beverage tank 51 are completely surrounded by heat insulating packing 59 of cork or the like which is interposed between the tank and the walls of the casing structure. This packing minimizes absorption of heat from the surrounding atmosphere of both the tanks 7 and 51.

In the operation of my improved cooling apparatus, when intermittently the draft faucets 54 are opened for the dispensing of the beverage, the latter is drawn from the supply in the tank 51. This withdrawal of liquid from the tank 51 lowers the liquid level therein and thereupon the float valve 52 is opened to admit more liquid and restore the level in the tank. Such additional liquid, entering through the inlet pipe 49 at a temperature above that to which it is to be cooled, passes into the coil 48 which is immersed in the liquid refrigerant in the tank 7. Here the liquid to be cooled gives up its heat directly to the metal wall of the tube and the latter in turn delivers this heat to the liquid refrigerant surrounding it with the result that some of the liquid refrigerant in contact with the tube is vaporized and rises through the liquid refrigerant to the vapor space at the top of the tank. As this action continues, more and more vapor accumulates in the top of tank 7 with increase of pressure, and the temperature of the liquid refrigerant correspondingly rises. As soon as the temperature rises to a certain predetermined point, however, the expansion of the fluid in the bulb 21 closes the switch 20 and starts the electric motor 11 which drives the compressor 10. The operation of the compressor draws the vaporized refrigerant from the top of the tank 7, compresses it, discharges it into condenser 12 where it is liquefied and whence in turn it passes through the pipe 17 back to the tank 7 into which it is admitted by the float valve 18, 19. The withdrawal of the refrigerant vapor from the tank 7 by the compressor reduces the pressure in the tank and permits more rapid vaporization of the refrigerant as the latter absorbs heat from the liquid in the cooling coil. The rapid vaporization continues until the temperature of the liquid refrigerant in the tank 7 is lowered to a predetermined point whereupon the contraction of the thermostatic fluid in the bulb 21 results in the opening of the motor switch and the stopping of the compressor.

The length of time during which the compressor will remain in operation for any one closing of the motor switch depends upon the rate at which the beverage or liquid to be cooled is drawn through the cooling coil and also upon the heat content of that

liquid. I prefer to so proportion to each other the dimensions of the cooling coil, i. e. its cross sectional capacity and its length, the maximum rate of draft of the liquid to be cooled, and the capacity of the refrigerant liquefying apparatus for removing vaporized refrigerant from the tank 7, that within the limits of variations of temperature of the liquid to be cooled, the refrigerant liquefying apparatus when in full operation will remove refrigerant vapor from the cooling tank or vaporizer as rapidly as said vapor is formed and that the exit temperature of the liquid cooled will not vary substantially from the temperature of the liquid refrigerant in the vaporizer. With such a relationship established, the apparatus has very remarkable capacity, efficiency and temperature regulating characteristics which I believe have never before been attained.

In Fig. 5 of the drawing I have shown a modified form of the thermostatic control. Here, the capillary tube connected with the thermostatic switch, instead of leading to a bulb immersed in the liquid refrigerant, leads into the low pressure or suction side of the refrigerant system. In the modified construction illustrated, 20 is the thermostatic switch, 22^a is the capillary tube and it is conveniently connected to communicate with the suction pipe 15 which connects the vapor space of the vaporizer tank 7 to the suction inlet of the compressor. With this construction the bellows device which actuates the thermostatic switch is subject to the vapor pressure in the tank 7 and inasmuch as this pressure varies directly with the temperature of the liquid refrigerant, the switch can be adjusted to suitably start and stop the compressor to maintain the temperature of the liquid refrigerant within the desired range. Consequently with this modified control the cycle of operation is the same as above described.

In order that the nature of my improvements may be understood as clearly as possible I will here give data by way of example for a characteristic embodiment of the invention in a cooler for drinking water. Let it be assumed that the cooler is to supply drinking water for steel mill workers and that it is desired to maintain the temperature of the water as near 50° F. as possible, this temperature being recognized as suitable for men working under such conditions. The consumption and wastage of water for such service is found to approximate two gallons per man per eight-hour day. Assuming that the temperature of the water available is 80° F., which is a typical summer temperature, the cooler will be required to lower the temperature 30 degrees. Each cooler would serve approximately one hundred men, which would mean approxi-

mately 200 pounds of water to be cooled per hour or an absorption of 6000 B. t. u. per hour. A suitable capacity for the compressor to be used in this case, allowing for the fact that under other conditions it may be called upon for service substantially below 50° F., is one having a normal A. S. R. E. rating of about 2500 B. t. u. per hour. A compressor of this capacity would have the following approximate ratings in B. t. u. per hour at various suction temperatures:

30°	5500	B. t. u.
40°	6900	B. t. u.
50°	8500	B. t. u.

For this capacity of cooler it has been found that a coil of nickel tubing of $\frac{7}{16}$ " outside diameter with 0.035" thick wall having a submerged length of 36 feet will transmit the heat from the water to be cooled to the refrigerant at the rate of 8500 B. t. u. per hour. The thermostatic switch of the compressor will be set to cut out at 47° F., and to cut in at 53° F., thus limiting variation of the exit water temperature to 3 degrees from the desired temperature of 50 degrees.

An operating cycle of this typical cooler is as follows: The compressor having been automatically stopped at the minimum temperature of 47° F., of the liquid refrigerant or cooling coil, water is now drawn through the cooler, entering at 80° F. The temperature of the coil is raised, resulting in a rise of the liquid refrigerant temperature, with resulting vaporization of the liquid refrigerant in contact with the coil. The coil is constantly maintained at approximately the liquid refrigerant temperature and the temperature of both continues to rise until 53° F. is reached when the thermostatic switch is closed and the compressor started. Refrigerant vapor is now withdrawn from the vaporizer and condensed by the compressor at its rated capacity, the cooling effect of the resulting rapid vaporization preventing further rise of the liquid refrigerant temperature. If the rate of draft of water is at the maximum capacity of the compressor employed, the compressor will continue to run until the draft is lessened or stopped, whereupon the temperature of the liquid refrigerant and coil will be lowered rapidly to the cut out temperature, namely 47° F., at which point the thermostatic switch is opened and the compressor stopped. This cycle will be repeated whenever sufficient heat is carried to the evaporator tank to raise the liquid refrigerant again to the cut in temperature of 53° F.

In the above example, for the sake of definiteness, a temperature of 80° F. is assumed for the water entering the cooler, but under some conditions the temperature and heat content of the water to be cooled may vary

considerably in the case of drinking water with small temperature head and there is and this, as well as the rate of draft, will affect the frequency and length of operation of the refrigerant liquefying apparatus. Furthermore, in some cases of liquid cooling to which the invention is applicable the variation of the temperature and heat content of the entering liquid, rather than the rate of draft of the liquid, may constitute the major variable factor or even the sole variable factor. However, in all cases of variable duty, the heat content of the liquid to be cooled per unit of time varies, and whether this latter variation be due to variable rate of draft or variable entering temperature of the liquid to be cooled, or to both of these, my improved apparatus automatically takes care of the variation.

My improved cooling apparatus has certain notable advantages over any prior liquid cooling apparatus known to me. One advantage is that as the rate of draft or the heat content of the liquid to be cooled varies, the amount of heat removed by the refrigerant varies in the same proportion and consequently the temperatures both of the liquid refrigerant and of the liquid drawn are constantly kept within the narrow range between the cut in and cut out temperatures. The exit water temperature of 50° F., for example, is relatively high in comparison with the refrigerant temperatures in liquid cooling systems in which ice is formed and the water or beverage is cooled by the ice. By keeping the liquid refrigerant temperature at the relatively high value indicated the compressor operates at close to maximum capacity in terms of mass of vapor handled and at very high efficiency in terms of B. t. u. handled per unit power consumption.

A further advantage, related to that last referred to, is that the heat absorption from the surrounding atmosphere is minimized because the liquid refrigerant and the metal parts are maintained at the (relatively high) temperature of the cooled liquid, say 50° F., whereas in ice maintaining coolers the cooling bath and metal parts of the apparatus are maintained at a temperature of approximately 32° F.

Both of the advantages last referred to above are, of course, dependent upon the maintenance of the previously described relation between the cooling tube or conduit, the maximum rate of draft of the liquid cooled and the maximum capacity of the compressor, together with the automatic control of the operation of the compressor.

Still another advantage is found in the extremely high efficiency of the relatively direct heat interchange between the liquid to be cooled and the liquid refrigerant, the two liquids being separated only by the one thin metal wall so that heat is conducted rapidly

70 to convection circulation such as occurs when a cooling bath of water, brine or the like surrounds the conduit or container of the liquid to be cooled.

Again, by reason of the extremely high efficiency of the direct heat interchange between the liquid to be cooled and the refrigerant the heat interchange surfaces can be 75 reduced to a minimum; and in addition the highly efficient heat interchange gives rapid cooling so that it is not necessary to maintain any considerable body of cooled liquid to meet prolonged drafts thereof. Both of 80 these circumstances favor compactness and the cooling unit of my apparatus is in fact exceedingly compact, cooling capacity considered. By cooling unit it will be understood that I mean that part of the refrigerant circuit and that part of the circuit of the liquid to be cooled which are in heat interchanging relation to each other. In the particular construction illustrated the cooling unit consists of the tanks 7 and 51 and their working parts, the tank 7 and its parts forming what may be termed a primary cooling unit while the tank 51, and its parts may be considered a secondary cooling unit. Of course, if the dispensing faucets 85 are connected directly to pipe 50, the tank 7 and its parts compose the cooling unit.

A still further advantage flows from the compactness of the primary cooling unit. That is to say, this cooling unit for even 100 relatively large capacities can be kept within such limited bounds that the element of space is not a controlling factor and it is entirely feasible to use the same cooling unit 105 for a considerable range of capacities and large scale production at low cost is thus favored.

Again, my cooler presents the marked advantage of uniformly close regulation of the exit water temperature, and this advantage 110 arises from the combined results of (a) properly relating the cooling coil and the capacity of the refrigerant liquefying means in relation to each other and to the maximum draft and heat content of the liquid 115 to be cooled, (b) rapid heat interchange, (c) automatic starting and stopping of the refrigerant liquefying means, and (d) the directing of the liquid to be cooled in a definite path through the cooling unit so that liquid entering the unit at high temperature 120 cannot possibly mingle with low temperature liquid being withdrawn.

It is to be observed that in the case of the form of apparatus illustrated, advantage 125 may be taken of the upper tank not only to relieve excess gas pressure but also to perform an additional function which in some instances may be of considerable value. As has been pointed out, the upper tank 51 is

in heat conducting relation to the lower tank 7 so that the liquid in the upper tank is maintained at substantially the same temperature as that of the liquid refrigerant in the lower 5 tank or cooling unit. For this reason it is possible for given service conditions to use cooling apparatus of somewhat smaller capacity than would otherwise be possible without seriously interfering with the close temperature regulation of the dispensed liquid 10 which it is desired to maintain. Thus the cooling unit and refrigerant liquefying means may have a somewhat smaller capacity than would otherwise be provided to take care of the extreme peak load on the cooler, because when the relatively infrequent peak load occurs even if the liquid is not reduced quite to the desired and predetermined temperature range in the primary cooling unit, 15 since this liquid is delivered into a substantial mass of liquid in the upper tank which is at a temperature within the predetermined range, the liquid drawn from the upper tank under such conditions will vary but slightly 20 from the predetermined temperature range and decidedly less than it would vary if under the same conditions the draft were made direct from the coil of the cooling unit. Obviously this feature can be taken advantage of whether the liquid being cooled is carbonated or not. The essential thing so far as this feature is concerned, is the provision of the supplemental reservoir into 25 which the liquid is discharged after passing through the cooling conduit and which holds said liquid in such relation to the refrigerant that the latter keeps the liquid in the reservoir substantially at the temperature of the refrigerant. 30 From what has been said in connection with the advantages above enumerated, it will be clear that a number of the features of the apparatus are peculiarly interdependent. For example, the provision of the refrigerant liquefying means of sufficiently 35 large capacity to take care of the cooling of the liquid substantially as rapidly as it may flow is necessitated by the nature of the heat interchange devices employed. In liquid cooling systems heretofore used in practice, the capacity of the refrigerant liquefying means and the maximum rate of draft of the liquid cooled are much less interdependent and their relation to each other is much less 40 important than in the case of applicant's apparatus, because in the prior systems it has been customary to hold considerable bodies of cooled liquid and in some instances of ice as well, to take care of peak loads. In applicant's primary cooler system, on the other hand, the provision of the refrigerant liquefying means with capacity of the character specified is essential to secure the rapid heat interchange that is effected between the liquid to be cooled and the refrigerant when 45 the latter is being drawn at maximum rate. In the operation of the device, when the refrigerant liquefying means is started by the automatic control devices the adequate capacity of the liquefying means very quickly withdraws the accumulated refrigerant vapor from the cooling unit, thus insuring evaporation of the refrigerant at the rapid rate necessary to maintain the operation of the cooling unit at maximum capacity. The provision of the refrigerant liquefying means with automatic control and of the suitable capacity specified in combination with the direct heat interchange type of cooling means produces an apparatus that is extremely flexible in its adaptability to widely varying loads. In this connection it is to be observed that the refrigerant liquefying means is kept in operation a smaller proportion of the time due to the rapid rate of cooling, thus minimizing wear in the case of the compressor type of liquefier.

While I have shown a specific form and type of apparatus for the purpose of explaining and illustrating the invention, it will be understood that the construction of the apparatus can be varied widely without departing from the invention. Obviously use can be made of any form of refrigerant liquefying means adapted to withdraw the refrigerant vapor from the cooling unit at a suitable rate and have its operation automatically controlled. And in the case of the primary cooling unit itself, while I prefer to maintain therein a definite mass of liquid refrigerant and to pass the liquid to be cooled through a conduit immersed in the liquid refrigerant, it will be understood that the means for admitting the refrigerant into the cooler may be any sort of controlling means that will automatically admit more or less of the refrigerant in liquid form, the advantages of my invention being attained to at least some degree if there is provided a conduit for the liquid to be cooled adapted to cause the flow of said liquid in a definite path through the cooling unit together with a vaporizing chamber directly associated with the said conduit and containing in operation liquid refrigerant in direct heat interchange relation with a wall of the said conduit and the liquid to be cooled on the other side of said wall. Again, it is quite obvious that the means employed for automatically controlling the refrigerant liquefying means may be any form of thermostatic or thermo-pressure device responsive to change of the temperature of the liquid refrigerant in the cooling unit.

Similarly, while I have shown the invention as embodied in cooling apparatus for dispensing charged beverages, it is obvious from what has been said in the description of the apparatus that the invention is applicable to a great variety of uses such, for ex-

ample, as the cooling of drinking water on draft, the cooling of water and beverages dispensed from soda fountains, and in fact the cooling of any flowing liquid having a variable or intermittent flow or a variable temperature, or both where it is desired closely to regulate the temperature of the cooled liquid.

What I claim is:

1. In apparatus for cooling liquids on draft, the combination of a closed refrigeration system including means for liquefying refrigerant vapor and a vaporizer chamber adapted to receive the liquefied refrigerant; a conduit for the liquid to be cooled comprising a metal section having its wall in contact on one side with the liquid refrigerant in the vaporizer; draft means associated with the conduit by which the liquid to be cooled is subject to draft intermittently at variable rates; and means operating automatically with change of temperature of the liquid refrigerant in the vaporizer chamber to vary the operation of the refrigerant in liquefying means and thereby maintain the temperature of the said liquid refrigerant within a limited predetermined range; the said section of the conduit being proportioned to direct the liquid to be cooled in a predetermined path and the said section of conduit, the maximum rate of draft of the liquid to be cooled and the maximum capacity of the refrigerant liquefying means to remove refrigerant vapor from the vaporizer chamber per unit of time being relatively proportioned to insure contact of the liquid drawn with the other side of the wall of said conduit section for a time sufficient to insure that substantially all of the sensible heat of the liquid to be cooled in excess of that corresponding to the maximum temperature of the said predetermined range shall be conducted from the liquid drawn directly through the wall of said conduit section to the refrigerant during the passage of the liquid through said conduit section.

2. In apparatus for cooling liquids on draft, the combination of a closed refrigeration system including a means for liquefying refrigerant vapor, a vaporizer chamber, and means operating in conjunction with the refrigerant liquefying means for automatically maintaining a body of liquid refrigerant in said chamber; a conduit for the liquid to be cooled comprising a metal section immersed in the said body of liquid refrigerant; draft means associated with the conduit by which the liquid to be cooled is subject to draft intermittently at variable rates; and means operating automatically with change of temperature of the liquid refrigerant in the vaporizer chamber to stop and start the compressor and thereby maintain the temperature of the said liquid refrigerant within a limited predetermined range; the said immersed section of the conduit being proportioned to direct the liquid to be cooled in a predetermined path and the said immersed section of conduit, the maximum rate of draft of the liquid to be cooled and the maximum capacity of the compressor to remove refrigerant vapor from the vaporizer chamber per unit of time being relatively proportioned to insure contact of the liquid to be cooled with the inner surface of said conduit section for a time sufficient to insure that substantially all of the sensible heat of the liquid to be cooled in excess of that corresponding to the maximum temperature of the said predetermined range shall be conducted from the said liquid directly through the wall of said conduit section to the refrigerant during the passage of the liquid through said conduit section.

3. In apparatus for cooling liquids on draft, the combination of a closed refrigeration system including a motor driven compressor, a condenser, a vaporizer chamber, and means operating in conjunction with the compressor and condenser for automatically maintaining a body of liquid refrigerant in said chamber; a conduit for the liquid to be cooled comprising a metal section immersed in the said body of liquid refrigerant; draft means associated with the conduit by which the liquid to be cooled is subject to draft intermittently at variable rates; and means operating automatically with change of temperature of the liquid refrigerant in the vaporizer chamber to stop and start the compressor and thereby maintain the temperature of the said liquid refrigerant within a limited predetermined range; the said immersed section of the conduit being proportioned to direct the liquid to be cooled in a predetermined path and the said immersed section of conduit, the maximum rate of draft of the liquid to be cooled and the maximum capacity of the compressor to remove refrigerant vapor from the vaporizer chamber per unit of time being relatively proportioned to insure contact of the liquid to be cooled with the inner surface of said conduit section for a time sufficient to insure that substantially all of the sensible heat of the liquid to be cooled in excess of that corresponding to the maximum temperature of the said predetermined range shall be conducted from the said liquid directly through the wall of said conduit section to the refrigerant during the passage of the liquid through said conduit section.

4. In apparatus for cooling liquids on draft, the combination of a closed refrigeration system including means for liquefying refrigerant vapor and a vaporizer chamber adapted to receive the liquefied refrigerant; a conduit for the liquid to be cooled comprising a metal section having its wall in contact on one side with the liquid refrigerant in the vaporizer; draft means associated with the conduit by which the liquid to be cooled is subject to draft intermittently at variable rates; and means operating automatically with change of temperature of the liquid refrigerant in the vaporizer chamber to stop and start the refrigerant liquefying means and thereby maintain the temperature of the said liquid refrigerant within a limited predetermined range.

contact on one side with the liquid refrigerant in the vaporizer; a reservoir for liquid to be cooled into which the said metal conduit section delivers liquid that has passed therethrough, the liquid in the reservoir being maintained in heat interchanging relation with the liquid refrigerant in the vaporizer chamber; draft means by which the cooled liquid in the reservoir is subject to draft intermittently at variable rates; and means operating automatically with change of temperature of the liquid refrigerant in the vaporizer chamber to vary the operation of the refrigerant liquefying means and thereby maintain the temperature of the said liquid refrigerant within a limited predetermined range; the said section of the conduit being proportioned to direct the liquid to be cooled in a predetermined path and the said section of conduit, the maximum rate of draft of the liquid to be cooled and the maximum capacity of the refrigerant liquefying means to remove refrigerant vapor from the vaporizer chamber per unit of time being relatively proportioned to insure contact of the liquid drawn with the other side of the wall of said conduit section for a time sufficient to insure that substantially all of the sensible heat of the liquid to be cooled in excess of that corresponding to the maximum temperature of the said predetermined range shall be conducted from the liquid drawn directly through the wall of said conduit section to the refrigerant during the passage of the liquid through said conduit section.

5. In apparatus for cooling liquids on draft, the combination of closed refrigeration system including means for liquefying refrigerant vapor and a metal walled vaporizer chamber adapted to receive the liquefied refrigerant; a conduit for the liquid to be cooled comprising a metal section having its wall in contact on one side with the liquid refrigerant in the vaporizer, said section of conduit being adapted to direct the liquid to be cooled in a predetermined path; a metal walled reservoir for liquid to be cooled into which the said metal conduit section delivers liquid that has passed therethrough; the walls of the reservoir and vaporizer being joined together to form a metallic heat flow path through both of said walls between the liquid in the reservoir and the liquefied refrigerant in the vaporizer; draft means by which the cooled liquid in the reservoir is subject to draft intermittently at variable rates; and means operating automatically with change of temperature of the liquid refrigerant in the vaporizer chamber to vary the operation of the refrigerant liquefying means and thereby maintain the temperature of the said liquid refrigerant within a limited predetermined range.

6. In apparatus for cooling carbonated beverages on draft, the combination of a closed refrigeration system including means for liquefying refrigerant vapor and a vaporizer chamber adapted to receive the liquefied refrigerant; a conduit for the carbonated liquid to be cooled comprising a metal section having its wall in contact on one side with the liquid refrigerant in the vaporizer; a reservoir for the carbonated liquid into which the said metal conduit section delivers liquid that has passed therethrough, the liquid in the reservoir being maintained in heat interchanging relation with the liquid refrigerant in the vaporizer chamber; automatic means for admitting the carbonated beverage into the said reservoir so as to maintain it at a predetermined level therein; means communicating with the space above the said liquid level for exhausting the charging gas above a predetermined pressure; draft means by which the cooled liquid in the reservoir is subject to draft intermittently at variable rates; and means operating automatically with change of temperature of the liquid refrigerant in the vaporizer chamber to vary the operation of the refrigerant liquefying means and thereby maintain the temperature of the said liquid refrigerant within a limited predetermined range; the said section of the conduit being proportioned to direct the carbonated liquid to be cooled in a predetermined path and the said section of conduit, the maximum rate of draft of the liquid to be cooled and the maximum capacity of the refrigerant liquefying means to remove refrigerant vapor from the vaporizer chamber per unit of time being relatively proportioned to insure contact of the liquid drawn with the other side of the wall of said conduit section for a time sufficient to insure that substantially all of the sensible heat of the liquid to be cooled in excess of that corresponding to the maximum temperature of the said predetermined range shall be conducted from the liquid drawn directly through the wall of said conduit section to the refrigerant during the passage of the liquid through said conduit section.

7. In apparatus for cooling flowing liquids, the combination of a closed refrigeration system including means for liquefying refrigerant vapor and a vaporizer chamber adapted to receive the liquefied refrigerant; a conduit for the liquid to be cooled comprising a metal section having its wall in contact on one side with the liquid refrigerant in the vaporizer; means associated with the conduit causing variation of the heat content of the liquid entering said metal section of the conduit per unit of time; and means operating automatically with change of temperature of the liquid refrigerant in the vaporizer chamber to

vary the operation of the refrigerant liquefying means and thereby maintain the temperature of the said liquid refrigerant within a limited predetermined range; the 5 said section of the conduit being proportioned to direct the liquid to be cooled in a predetermined path and the said section of conduit, the maximum heat content to be removed from said liquid per unit 10 of time and the maximum capacity of the refrigerant liquefying means to remove refrigerant vapor from the vaporizer chamber per unit of time being relatively proportioned to insure contact of the flowing liquid 15 with the other side of the wall of said conduit section for a time sufficient to insure that substantially all of the sensible heat of the liquid to be cooled in excess of that corresponding to the maximum temperature 20 of the said predetermined range shall be conducted from the liquid to be cooled directly through the wall of said conduit section to the refrigerant during the passage of the liquid through said conduit section. 25

8. In apparatus for cooling flowing liquids, the combination of a closed refrigeration system including a means for liquefying refrigerant vapor, a vaporizer chamber, and means operating in conjunction with the 30 refrigerant liquefying means for automatically maintaining a body of liquid refrigerant in said chamber; a conduit for the liquid to be cooled comprising a metal section immersed in the said body of liquid refrigerant; means associated with the conduit causing variation of the heat content of the liquid entering said metal section of the conduit per unit of time; and means operating automatically with change of temperature of the liquid refrigerant in the 35 vaporizer chamber to stop and start the refrigerant liquefying means and thereby maintain the temperature of the said liquid refrigerant within a limited predetermined range; the said immersed section of the conduit being proportioned to direct the liquid to be cooled in a predetermined path and the said immersed section of conduit, the maximum heat content to be removed from said liquid per unit of time and the maximum capacity of the refrigerant liquefying means to remove refrigerant vapor from the vaporizer chamber per unit of time being relatively proportioned to insure contact of the flowing liquid with the inner surface of said conduit section for a time sufficient to insure that substantially all of the sensible heat of the liquid to be cooled in excess of that corresponding to the maximum temperature of the said predetermined 40 range shall be conducted from the liquid to be cooled directly through the wall of said conduit section to the refrigerant during the passage of the liquid through said conduit section. 45

10. In apparatus for cooling flowing liquids, the combination of a closed refrigeration system including means for liquefying refrigerant vapor and a vaporizer chamber adapted to receive the liquefied refrigerant; a conduit for the liquid to be cooled comprising a metal section having its wall in contact at one side with the liquid refrigerant in the vaporizer; a reservoir for liquid to be cooled into which the said metal conduit section delivers liquid that has passed therethrough, the liquid in the reservoir being maintained in heat interchanging relation with the liquid refrigerant in the vaporizer chamber; means associated with the conduit causing variation of the heat content of the liquid entering said metal section of the conduit per unit of time; and means operating automatically with change of temperature of the liquid refrigerant in the 50 vaporizer chamber to vary the operation of the refrigerant liquefying means and thereby maintain the temperature of the said liquid refrigerant within a limited predetermined range; the said section of the con- 55

- duit being proportioned to direct the liquid to be cooled in a predetermined path and the said section of conduit, the maximum heat content to be removed from said liquid 5 per unit of time and the maximum capacity of the refrigerant liquefying means to remove refrigerant vapor from the vaporizer chamber per unit of time being relatively proportioned to insure contact of the flowing 10 liquid with the other side of the wall of said conduit section for a time sufficient to insure that substantially all of the sensible heat of the liquid to be cooled in excess of that corresponding to the maximum temperature of 15 the said predetermined range shall be conducted from the liquid to be cooled directly through the wall of said conduit section to the refrigerant during the passage of the liquid through said conduit section.
- 20 11. In apparatus for cooling flowing liquids, the combination of a closed refrigeration system including means for liquefying refrigerant vapor and a metal walled vaporizer chamber adapted to receive the liquefied refrigerant; a conduit for the liquid to be cooled comprising a metal section having
- its wall in contact on one side with the liquid refrigerant in the vaporizer, said section of conduit being adapted to direct the liquid to be cooled in a predetermined path; a metal walled reservoir and vaporizer for liquid to be cooled into which the said metal conduit section delivers liquid that has passed therethrough; the walls of the vaporizer and reservoir being joined together to form a metallic heat flow path through both of said walls between the liquid in the reservoir and the liquefied refrigerant in the vaporizer; means associated with the conduit causing variation of the heat content of the liquid 30 entering said metal section of conduit per unit of time; and means operating automatically with change of temperature of the liquid refrigerant in the vaporizer chamber to vary the operation of the refrigerant liquefying means and thereby maintain the temperature of the said liquid refrigerant within a limited predetermined range.
